UNITED STATES PATENT OFFICE.

JOHN C. STOKES, OF SHREVEPORT, LOUISIANA.

DRILL AND UNDERREAMER.

Application filed August 17, 1920. Serial No. 404,240.

To all whom it may concern:

Be it known that I, JOHN C. STOKES, a citizen of the United States, residing at Shreveport, in the parish of Caddo and 5 State of Louisiana, have invented certain new and useful Improvements in Drills and Underreamers, of which the following is a specification.

This invention relates to drills and underreamers and is an improvement on my Patent No. 1,379,483, issued May 24, 1921, and on my Patent No. 1,360,328, issued November 30, 1920.

The principal object of the invention is 15 to provide an improved means of forming the fluid washing channels in the legs of the drill bit carrier, so that the same can be easily made therein and so that the débris will be effectively washed from 20 around the bit blades.

With this and other objects in view, the invention consists in the novel construction, arrangement and formation of parts as will be hereinafter more specifically described, 25 claimed and illustrated in the accompanying drawings, forming a part of this specification, in which drawings:

Figure 1 is a vertical longitudinal section through the improved drill and underreamer showing the blades of the drill bit in operative position and a grapple or overshot in operative position for raising the drill bit and carrier from the drill holder and stem.

Figure 2 is an elevation of the grapple or overshot.

Figure 3 is a detail transverse section through the drill taken on the line 3-3 of Figure 1.

Figure 4 is a fragmentary vertical section through the drill bit carrier and grapple in operative position in relation to each other illustrating the type of dogs utilized for lowering the drill bit and carrier into 45 the stem and holder.

Figure 5 is a detail section taken on the line 5-5 of Figure 2.

Figure 6 is an enlarged elevation of the improved drill bit carrier.

Figure 7 is a vertical longitudinal section through the same taken on the line 7-7 of Figure 6.

Figure 8 is a fragmentary longitudinal section through the drill bit carrier taken on the line 8-8 of Figure 6.

55

Figure 9 is a transverse section through the carrier taken on the line 9-9 of Figure 6.

60

Figure 10 is a similar section taken on the line 10-10 of Figure 6.

65

Referring to the drawings in detail, wherein similar reference characters designate corresponding parts throughout the several views, the letter A generally indicates the improved drill which includes the holder or drill stem B, the bit carrier C, and the drill bit D; and E, the grapple or overshot.

The tool holder or drill stem B includes a cylindrical body 15 having an annular flange 16 formed on its inner surface adjacent to the lower end thereof, which defines the upper and lower shoulders 17 and 18 which are adapted to be engaged by the bit D when the same is in its extended operative position.

70

The inner surface of the cylindrical body 15 below the shoulder 18 is gradually increased in diameter toward its lower end as at 19, and this inclined portion is provided with one or more pairs of oppositely disposed longitudinally extending ribs (not shown in the present drawings), and which are adapted to form stops for the bit D. The upper inner face of the cylindrical body 15 above the upper shoulder 17 is enlarged in diameter as at 21 which forms a shoulder which is ground to form an inclined seat or bearing 22, the purpose of which will be hereinafter more specifically described.

75

The bit carrier C comprises a solid body 23 of cylindrical formation whose diameter is substantially equal to the internal diameter of the enlarged portion 21 of the bore of the hollow cylindrical body 15 and the lower end of the same is bevelled to form an annular face 24 which is adapted to fit on the seat or bearing face 22 so as to form a tight fit or seal between the bit holder B and the carrier C. This prevents the seeping of water by the drill bit carrier

80

when the same is in its lowermost position. The lower end of the body 23 is notched as at 25 on its opposite sides so as to re-

85

90

95

100

ceive the depending bit carrier legs 26. The upper terminals of the legs 26 are secured to the body 23 by bolts and nuts 27 and the nuts may be countersunk if so desired.

5 The legs 26 are provided with water channels 28 for cleaning the bit blades D.

The arrangement and formation of the water channels 28 form an important part of the invention and it is to be noted that 10 these channels extend from the upper terminals of the legs to the lower free ends thereof and the inner faces of the legs on one side of the longitudinal center thereof are provided with longitudinal grooves 29 and the 15 upper ends of the legs are notched as at 30 which forms entrance ports for the water or other cleaning fluid. As clearly shown in Figure 6 of the drawings, the side walls of the slots 29 are gradually converged toward 20 the free ends of the legs so that the cleaning fluid will be placed under pressure when the same flows into engagement with the bit blades D. Tapered cover plates 31 are provided for the grooves 29 and these cover 25 plates 31 extend from the lower edge of the body 23 to the lower edges of the legs 26 and these cover plates may be brazed, welded or otherwise secured to the side walls of the grooves and these cover plates are adapted 30 to extend flush with the inner surfaces of the legs. As shown the opposite side walls of the grooves are dove-tailed as at 32 and the side edges of the cover plates are shaped accordingly and the same are adapted to be 35 slid into position. The means for forming the water channels 28 in the legs 26 eliminates the necessity of boring the legs longitudinally and thus simplifies the making of these channels and it can be seen that 40 when the cover plates 31 are connected to the legs as shown in the drawings the same can be readily removed when desired for permitting the thorough cleaning of the channels. The covers 31 are provided intermediate 45 their ends with openings 31'. These openings 31' are formed in the covers for a purpose which will be hereinafter more specifically described.

If so desired the bit carrier C directly below the inclined face 24 may be provided 50 with any suitable type of piston rings 33 for frictional engagement with the inner face of the drill holder B so as to absolutely preclude the passage of the cleaning fluid 55 between the drill holder and the bit carrier C.

The bit D includes a pair of spaced plates or blades 34 and 35 which have their outer edges provided with shoulders 36 and 37 60 for engaging the lower edge of the tool holder and the shoulder 18. The upper ends of the blades 34 and 35 are provided with oppositely directed extensions which provide shoulders 38 which are adapted to engage 65 the annular shoulder 17 when the blades are

in their lowermost extended positions. The blades 34 and 35 are provided adjacent their inner edges with inclined slots 39 and the upper and lower ends of these slots may terminate in angular extensions 40. These 70 slots 39 are adapted to receive the pivot pin 41 which is of special construction and this pin is carried by the lower terminals of the legs 26 of the bit carrier C. The upper angular straight extensions 40 of the slots 75 are provided so as to permit the blades to be held in line and these angular extensions extend parallel with the longitudinal medial lines of the blades. The purpose of the openings 31' in the covers 31 of the legs 26 80 is to permit a certain portion of the fluid in the channels to pass in the slots 39 to keep them washed out, so that the pin 41 will have free movement therein. The pivot pin 41 is provided with an enlarged head 42 85 which is countersunk in one of the legs 26, while the opposite end of the pin is provided with a reduced threaded extension 43. The reduced threaded extension is threaded into the other leg 26 and the same forms a shoulder 44 which limits the insertion of the bolt into the leg 26 and prevents the squeezing of the legs into frictional contact with the bit blades D. The pin 41 is held in place against accidental displacement by means of 90 a cotter pin 45 and the outer surface of the leg 26 can be grooved for receiving the same.

The upper end of the body 23 of the carrier C is provided, in the example shown, with an upwardly extending centrally disposed stem 46 which is provided with a conical head 47 for a purpose which will hereinafter more fully appear. The stem 46 has slidably mounted thereon the weight 48 which has its upper end tapered or rounded for a purpose which will also hereinafter more fully appear. The weight 48 normally engages the upper surface of the body 23 of the carrier C and is adapted to engage the head 49 of a sliding rod 50 for normally holding the same downwardly in its bore 51 which extends longitudinally through the body 23 of the carrier C. When the bit blades 34 and 35 reach the lower end of the holder C and are held against further downward movement, the lower end of the rod 50 will engage the blades and be forced upwardly therewith and raise the weight 48 therewith for a purpose which will now be described.

A raising and lowering device E, in the example shown is provided for facilitating the manipulation of the bit carrier in the drill stem and the same includes the solid cylindrical body 52 the lower end of which is bifurcated as at 53 for the reception of a pair of dogs 54 and a pair of dogs 55. The pairs of dogs 54 and 55 are freely interchangeable and the dogs 54 are utilized for hoisting the bit blades D and carrier C in 130

the holder and stem and the dogs 55 are utilized for lowering the bit carrier and blades in the bit holder B. The upper end of the body 52 is provided with a reduced 5 threaded extension 56 which receives the hollow cap 57. The hollow cap 57 is provided with a central aperture 58 through which is positioned the hoisting cable 59. The lower end of the hoisting cable 59 is leaded as 10 at 60 so that accidental displacement of the same from the cap 57 is eliminated.

The dogs 54 are pivotally connected to the body 52 by means of a removable pivot pin 61 and the lower terminals of the dogs 15 are provided with relatively sharp teeth 62 for engaging the conical head 47 of the stem 46. The lower edges of the teeth 62 are rounded as at 63 so that the dogs will be spread open on the pivot pin 61 when the 20 teeth 62 engage the conical head 47. The teeth 62 are of such a shape as to be readily inserted between the weight 48 and the conical head 47. The upper terminals of the dogs 54 above the pivot pin 61 are provided 25 with the right angularly extending legs 65 which normally tend, owing to the weight thereof, to hold the toothed ends of the dogs out of engagement with the conical head 47 of the stem 46. The free terminals of 30 the legs 65 extend beyond the sides of the body 52 for a purpose which will be herein-after more specifically described.

As stated the dogs 55 are adapted to be utilized when the bit carrier C is being lowered into the bit holder and when the dogs 35 55 are to be utilized instead of the dogs 54 the pin 61 is removed and the dogs 54 replaced by the dogs 55 and the pin 61 is again replaced. The dogs 55 are of the 40 same shape and operate in the same manner as the dogs 54 with the exception that the same are provided with relatively high teeth 66 for engagement with the conical head 47 of the stem 46. These teeth have their lower faces also curved as at 67 and they are formed relatively high so that when the 45 weight 48 is raised by the rod 50 the same will be operated and forced away from the head 47 so as to permit the automatic releasing of the raising and lowering device E from the carrier. The lower end of the carrier, at the bifurcation thereof, is also hollowed out and shaped as at 68 to conform to the configuration of the weight 48. If so desired suitable packing 69 may be placed 55 around the rod 50 so as to prevent the seeping of water or the like through the bore 51.

If for any reason, when the hoisting and lowering device E is lowered into the stem 60 and holder B for raising the bit carrier C the carrier becomes stuck in the bit holder and the same cannot be raised, it is merely necessary to lower a hollow cylindrical casing 70 on the hoisting cable 59 and it will 65 be seen that the casing will engage the ex-

tended terminals of the legs 65 of the dogs 54 and thereby swing the dogs on the pivot pins 61 and the teeth 62 thereof from out of engagement with the head 47. The raising and lowering device E can then be readily removed from the stem and other methods can be then pursued for removing the carrier from the bit holder.

Stop lugs 70' are carried by the opposite sides of the body 52 for limiting the downward movement of the shell 70 on the hoisting and lowering device.

Changes in details may be made without departing from the spirit or scope of this invention; but,

I claim:

1. In a drill apparatus, a bit carrier including a body and spaced legs, the inner faces and upper edges of the legs being provided with grooves, and cover plates carried by the legs and enclosing said grooves.

2. In a drill apparatus, a bit carrier including a body and depending spaced legs, the legs being provided with longitudinally extending grooves and cover plates carried by the legs and enclosing said grooves from said body to the terminals of said legs.

3. In a drill apparatus, a bit carrier including a cylindrical body and depending spaced legs, the inner faces of the legs being provided with longitudinally extending grooves and removable cover plates carried by the legs and arranged to enclose said grooves.

4. In a drill apparatus, a bit carrier including a cylindrical body and recesses formed in its opposite faces, depending legs having their upper terminals fitted in said recesses, the legs having their inner faces provided with longitudinally extending grooves extending from the upper ends of the legs to the lower ends thereof and their upper edges with notches, and cover plates carried by the inner faces of said legs and extending from the lower end of said body to the lower end of said legs.

5. In a drill apparatus, a bit carrier including a cylindrical body having recesses formed in its opposite faces and depending spaced legs, the upper terminals of the legs being arranged in said recesses, the inner faces of said legs being provided with longitudinally extending grooves and their upper edges with notches, the side walls of said grooves being dove-tailed and gradually converging toward the lower ends of the legs and tapered cover plates arranged to slidably fit within said dove-tailed grooves.

6. A drill comprising a tool holder, a bit carrier having a bifurcated lower end, a pair of bit blades arranged in the bifurcated end of the carrier, a pivot pin carried by the lower end of said carrier and arranged to receive said bit blades, said pin

including a reduced threaded end, said reduced threaded end forming a shoulder for engaging the inner face of the lower end of said bit carrier to limit the movement of the 5 pin therein.

7. In a drill apparatus, a bit carrier including a cylindrical body and depending spaced legs, a bolt carried by the lower end

of the legs, a pair of bit blades having slots arranged to receive the bolt, longitudinally extending channels formed in said legs, the channels having openings arranged to communicate with said slots to permit a certain portion of the fluid in said channels to flow in said slots.

JOHN C. STOKES.
